UNITED STATES PATENT OFFICE.

PAUL WILLIAM PICK, OF PORTLAND, OREGON.

ANTIRATTLER FOR WINDOW-SASHES.

1,386,024.

Specification of Letters Patent.

Patented Aug. 2, 1921.

Application filed June 7, 1920. Serial No. 387,057.

To all whom it may concern:

Be it known that I, PAUL WILLIAM PICK, a citizen of the United States, residing at Portland, in the county of Multnomah and 5 State of Oregon, have invented certain new and useful Improvements in Antirattlers for Window-Sashes, of which the following is a specification.

This invention relates to devices which 10 are used between a window sash and jamb, or, between a pair of window sashes at the meeting rails, for the purpose of tightening the sash or sashes and thereby preventing rattling when the wind is blowing.

15 My object is to provide a simple, inexpensive, durable and portable anti-rattler for window sashes which embodies improvements adapting it for quick and easy application to the sash at any point where it is 20 advisable to wedge the latter and prevent rattling.

My anti-rattler embodies a sheet metal sheath, preferably of steel, having relatively 25 expansible sides arranged so as to be adapted for easy insertion between the sash and the jamb, or, between the meeting rails of two sashes, and a movable wedging device or member, preferably pivoted to the sheath, which can be used with a lever-like action to 30 expand the sides of the sheath for the purpose of locking the sash.

My invention possesses the very decided 35 advantages of being light and portable and, also, adaptable for easy application, while preventing any damage to the sash or to the jamb or sash bead. The wedging device or member being used as an expander for the sides of the sheath and working between them, instead of being forced directly be- 40 tween the sashes or a sash and the jamb, does not mar the sash or jamb. The invention being capable of embodiment in very compact form, is particularly adapted for use by travelers and others who have occa- 45 sion to occupy rooms in hotels and other buildings where, from age or poor construction, the sashes are loose and inclined to rattle.

The invention being susceptible of modi- 50 fication without departing from the essential principle thereof, the disclosure is to be considered as illustrative, instead of re- strictive, of the scope thereof.

In the accompanying drawings:

Figure 1, is an elevation of a portion of 55 two window sashes and their jamb, illustrating the application of the anti-rattler;

Fig. 2, is a detail side view of the anti-rattler by itself, the wedging device being swung outwardly in relation to the sheath; 60

Fig. 3, is a detail plan view of the invention, when the wedging device is inside the sheath; and

Fig. 4, is an edge view, the parts being 65 in the condition shown in Fig. 3.

Portions of two window sashes are shown at 1 and 2, and a portion of their jamb at 3.

My invention comprises a sheath 4 and a wedging device or member 5 adapted for use in expanding the sides or walls of the 70 sheath when swung in between said sides or walls.

Preferably, the wedging device or mem- 75 ber 5 is in the form of a wedging lever hav- ing a handle 6 and pivoted at its other end to the sides of the sheath 4 at 7.

Preferably, the sheath 4 is in the form of a piece of doubled sheet steel whose free edges come together, or reasonably close to each other along the lines 8, 9. The inherent 80 resiliency of the stock of the sheath maintains the sides thereof normally in that condition so that the sheath may be easily inserted between the sash and the jamb, as shown in Fig. 1, or, between the meeting 85 rails of the sashes.

The device 5 is preferably made of hard metal and is of wedge shape in cross-section, and has the sharp edge 10, whereby it is readily forced between the sides of the 90 sheath 4.

To prevent a sash from rattling, the sheath 4 is slipped in between the sash and its jamb, or, between the meeting rails of the two sashes. The wedging device 5 is 95 then swung in between the sides of the sheath, by operating the handle 6 to bring the same to the position shown in Figs. 1, 3, 4, or as near thereto as circumstances may require. The wedging device works against 100 the inner faces of the sheath and expands them without marring the sash or jamb. To remove the device, the handle 6 is swung outwardly as shown in Fig. 2.

What I claim is:

1. An anti-rattler for window sashes, com-

prising a sheath formed from a doubled piece of sheet metal having relatively expandable sides, and a movable wedging device carried by the sheath and mounted so that it is adapted to be inserted between the sides of the sheath.

2. An anti-rattler for window sashes, comprising a sheath formed from a doubled

piece of sheet metal having relatively expandable sides, and a wedging device pivoted to said sheath and adapted to be inserted between the sides thereof to expand them, said wedging device having a handle.

In testimony whereof I affix my signature.

PAUL WILLIAM PICK,
